CABLE OR WIRE LINE CLAMP

Stephen Bullum, Overton, Tex., assignor of three-fourths to A. D. Gaston, Austin, Tex., and one-fourth to Bullum, Incorporated, Austin, Tex.

Application August 19, 1933, Serial No. 685,796

4 Claims. (Cl. 24—136)

This invention relates to new and useful improvements in cable or wire line clamps.

One object of the invention is to provide a wire line or cable clamp having improved means for 5 clamping a wire line or cable.

Another object of the invention is to provide a wire line or cable clamp having longitudinal channels therethrough for receiving the lines and means for clamping the lines in said channels, 10 said means being independently operable and so arranged that an opposite pull on the lines will tend to tighten said lines within the clamp.

A further object of the invention is to provide a wire line or cable clamp having longitudinal 15 channels therethrough for receiving the lines, a gear rack and gear being provided for each channel whereby the lines may be clamped within said channels, the gears being independently operable whereby the line in one channel may be 20 held in a clamped position while the other line is released.

A still further object of the invention is to provide a wire line or cable clamp having longitudinal channels therethrough for receiving the lines, 25 each channel having a wedge-shaped key slidable therein, the channels and keys having angled complementary faces whereby movement of the keys will move said keys into and out of clamping position and means for independently operating 30 the keys, said means being so arranged that an opposite pull on the lines will tend to move the keys into a tighter clamping position.

Another object of the invention is to provide a wire line or cable clamp having a pair of clamp- 35 ing wedge-shaped keys, each provided with a gear rack and a gear engaging said rack to move said key into and out of clamping position, the keys being independently operated in opposite directions, whereby a pull in one direction on one side 40 of the clamp tends to tighten the clamping key on that side by rolling the gear up the rack, while a pull in the opposite direction on the other side of the clamp tends to tighten the clamping key on that side by rolling its gear down its inclined 45 rack.

A construction designed to carry out the invention will be hereinafter described, together with other features of the invention.

The invention will be more readily understood 50 from a reading of the following specification and by reference to the accompanying drawings in which an example of the invention is shown, and wherein:

Figure 1 is a plan view of a clamp constructed 55 in accordance with the invention,

Figure 2 is a front elevation of the same, Figure 3 is a side elevation of the clamp showing the wire line clamped within the same and passing over a sheave,

Figure 4 is a transverse vertical sectional view, 5 Figure 5 is a perspective view of one of the clamping keys,

Figure 6 is a perspective view of one of the keepers, and

Figure 7 is a perspective view of one of the operating gear members. 10

In the drawings the numeral 10 designates an elongated clamp body or support. Longitudinal tapered openings or channels 11 extend through the body at each end face thereof. Each channel 15 is triangular in cross section throughout its length and each has a guideway 12 extending outwardly therefrom. A wedge-shaped key 13 is mounted to slide longitudinally in each channel and each key has a central longitudinal guide 14 on its 20 front side engaging in its respective guideway.

Each guide has a forwardly projecting boss 15 located nearer its lower end. This boss extends from the guideway and has a bearing recess 16 receiving a transverse shaft 17. The shaft is 25 confined within the recess by a keeper 18. The keeper is provided with a recess 19 at each side and fingers 20 project rearwardly from said keeper. Pins 21 on the boss 15 engage in apertures 22 in the keeper and by upsetting the ends of 30 these pins the keeper is fastened to the boss.

Vertical gear racks 23 are formed on each side of the clamp body 10 adjacent the end of each guideway 12 and extend longitudinally along each side of said guideway. Gears 24 fastened on the 35 shafts 17 are confined in the recesses 19 on each side of the bosses 15 and these gears engage the racks 23. Each shaft extends outwardly to one side and has a suitable operating handle 25 on its end. The fingers 20 of each keeper 18 overhang 40 the outer sides of the racks and guide said keeper. When one of the shafts 17 is rotated, its gears 24 are caused to travel up and down its respective racks 23, whereby the boss 15 and key 13 attached 45 to said shaft are longitudinally adjusted. From the foregoing description, it is obvious that each key 13 has its individual gear racks 23 and operating shaft 17, whereby each key may be operated independently of the other. Thus, if for any reason it is desired to change the position of one 50 of the lines with relation to the clamp, this line may be released and its position changed while the opposite line is held in a clamped position.

It will be noted that on each side of the guide 55 14 front faces 26 of the key are inclined down-

wardly and rearwardly. Within each channel 11 complementary inclines 27 are provided on each side of each guideway 12. By observing Figure 4, it is seen that the keys 13 are placed in the channels in opposite directions; that is, the key 13 at the forward end of the body is arranged to move inwardly within the channel when the shaft 17, attached thereto, is rotated to cause the gears to move the key downwardly; while the key 13 at the rear portion of the body is arranged to move inwardly within its channel 11 when its shaft 17 is rotated to cause its gears to travel upwardly.

Each key 13 has a general triangular shape to conform to the channel and is provided with a vertical concaved seat 28 in its inner side. The inner side of each channel forms a crotch 29 for receiving the wire line cable A. As each key is moved inwardly, it crowds the cable into the crotch and thus clamps it. Owing to the V-shape of each crotch, various sizes of cable may be clamped, the cable being wedged in said crotch by the key 13. A suitable handle 30 may, if desired, be made integral with the body of the clamp.

In Figure 3, I have shown one use of the clamp wherein the wire line or cable A is passed over a sheave 31. With this arrangement one side of the cable is pulling upwardly and the opposite side is pulling downwardly. By using the clamp as described, the downward pull on the forward key 13 (left side of Figure 3) will tend to move the gears 24 on the forward shaft 17 in a downward direction on their racks 23, thereby causing said key to more firmly clamp the cable. At the same time, the pull on the cable on the opposite key 13 will be in an upward direction, thereby causing the gears 24 on the shaft 17 of that key to travel upwardly along its gear racks 23 to more firmly clamp the cable in the rear channel 11. It is obvious that each shaft 17 is rotatable independently of the other, whereby each key may be independently adjusted to clamp the cable in its respective channel.

The device is not to be limited to any particular use for it is obvious many uses may be found. For instance, the clamp may be used to connect two pieces of cable. The arrangement of the keys 13 is an important feature of the invention as it allows for an opposite pull on each key, which serves to tighten the grip of the keys on the cable and provide for a positive clamping action.

The description which has been given recites more or less detail of a particular embodiment of the invention, which is set forth as new and useful, however, I desire it understood that the invention is not limited to such exact details of construction, because it is manifest that changes and modifications may be made within the scope of the appended claims without departing from the spirit of the invention.

What I claim and desire to secure by Letters Patent, is:

1. A rod or line clamp comprising, an elongated body provided with a tapered longitudinal channel which is triangular in cross-section, whereby the rod or cable in the channel is engaged at two spaced points on its surface, a wedge-shaped key in the channel engaging the rod or cable for forcing it into contact with the side walls of the channel and wedging it therein, whereby said rod or cable is securely clamped, a rack adjacent the longitudinal channel on the elongated body, and an actuating member on the back of the key extending at substantially right angles thereto and provided with a pinion for engaging said rack. 5

2. A rod or line clamp comprising, an elongated body provided with a tapered longitudinal channel which is triangular in cross-section, whereby the rod or cable in the channel is engaged at two spaced points on its surface, a wedge-shaped key in the channel engaging the rod or cable for forcing it into contact with the side walls of the channel and wedging it therein, whereby said rod or cable is securely clamped, a rack adjacent 10 each side of the channel on the elongated body and an actuating member on the back of the key extending at substantially right angles thereto and provided with pinions for engaging said racks for moving said key longitudinally of said channel 15 to wedge and release the rod or cable therein. 20

3. A rod or line clamp comprising, an elongated body provided with a tapered longitudinal channel which is triangular in cross-section, whereby the rod or cable in the channel is engaged at two spaced points on its surface, a wedge-shaped key in the channel engaging the rod or cable for forcing it into contact with the side walls of the channel and wedging it therein, whereby said rod or cable is securely clamped, a rack adjacent each 25 side of the longitudinal channel on the elongated body, and a keeper mounted on the back of said key, pinions confined by said keeper and engaging complementary racks, and means for rotating the pinions. 30

4. A rod or line clamp including, an elongated body having end faces, said body being provided with a longitudinal tapered channel extending through the end faces, said channel being of triangular cross section throughout its length, 35 whereby the rod or cable in the channel is engaged at two spaced points on its surface, a tapered key shaped to conform with said channel and slidable therein engaging the rod or cable for forcing it into contact with the side walls of the channel and wedging it therein, whereby said rod or cable is securely clamped, and means for moving said key longitudinally of said channel to wedge and release the rod or cable therein. 40

STEPHEN BULLUM. 60
